(57) **CLAIM**

The ornamental design for a piano, as shown and described.

DESCRIPTION

FIG. 1 is a perspective view of the front, top and right side of a piano showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front view thereof in which a keyboard cover is closed.

The broken line showing of the piano is included for the purpose of illustrating portions of the piano and forms no part of the claimed design.

The dot and dashed lines mean a boundary between the claimed portion and the non-claimed portion.

1 Claim, 7 Drawing Sheets
